(57) **CLAIM**

The ornamental design for a pen stand, as shown and described.

DESCRIPTION

FIG. 1 is a front elevational view of a pen stand showing our new design;

FIG. 2 is a rear elevational view thereof;

FIG. 3 is a side view, taken from the left side of FIG. 1;

FIG. 4 is a side view, taken from the right side of FIG. 1;

FIG. 5 is a top plan view thereof; and,

FIG. 6 is a bottom plan view thereof.

The broken line showing of a pen in FIG. 2 is for illustrative purposes only and forms no part of the claimed design.
